UNITED STATES PATENT OFFICE.

HERMAN TOASPERN, JR., OF BROOKLYN, NEW YORK.

DESIGN FOR A CALENDAR-CARD.

SPECIFICATION forming part of Design No. 14,465, dated December 4, 1881.

Application filed July 30, 1883. Term of patent 3½ years.

To all whom it may concern:

Be it known that I, HERMAN TOASPERN, Jr., a citizen of the United States, and a resident of Brooklyn, in the county of Kings and State 5 of New York, have invented and produced a new and useful Design for Calendar-Cards, of which the following is a full, complete, and exact specification, reference being had to the annexed drawing, which forms a part thereof.

10 The drawing shows a plan view of my design.

The design consists, principally, in producing on each side of the card intended for a calendar a raised surface having the form of 15 wave-like corrugations, gradually decreasing in size.

In the drawing, B is the calendar-card, on each side of which extend out perpendicularly to the same the corrugations, which are arranged so as to gradually decline toward the top of the card. In other words, each one of the corrugations is smaller in size than the preceding one. These corrugations are indicated by A.

What I claim as new, and desire to secure 25 by Letters Patent, is—

The design for calendar-cards, herein shown and set forth.

H. TOASPERN, JR.
